ELECTRICAL CIRCUIT, INCLUDING A
SWITCH AND PLUG MECHANISM

Walter J. Bauroth, Columbus, Ohio, assignor to
The Jeffrey Manufacturing Company, a corporation of Ohio

Original application May 1, 1943, Serial No.
485,291. Divided and this application March
8, 1948, Serial No. 13,648

11 Claims. (Cl. 318—103)

1

This invention relates to electrical circuits including at least two switches operated by a common operating means which is moved to operate the switches by a connector plug in one of the circuits.

One object of my invention therefore is to provide an improved mechanism for providing improved circuits of the type above set forth.

Another object of my invention is to provide improved electrical apparatus for a mining machine in which a pair of switches are contained preferably, but not necessarily, in a permissible, explosion or flame-proof box and are controlled by mechanism requiring one of the switches to be opened when one is closed and vice versa, one of said switches controlling the cutting motor for the mining machine and the other an auxiliary device that is to be operated such, for example, as a motor of a drill or water pump.

Other objects of the invention will appear hereinafter, the novel features and combinations being set forth in the appended claims.

In the accompanying drawings,

Fig. 1 is a sectional elevational view of the device of my invention, certain parts not being shown entirely in section in the interest of clearness;

Fig. 2 is a sectional view taken on the line 2—2 of Fig. 1, looking in the direction of the arrows;

Fig. 3 is a sectional view taken on the line 3—3 of Fig. 1, looking in the direction of the arrows;

Fig. 4 is an enlarged plan view of a portion of the box and plug with the operating sleeve of the plug shown in developed relation;

Fig. 5 is a plan view of the device of my invention with parts broken away and in section and with certain parts omitted in the interest of clearness;

Fig. 6 is a front elevational view of the device;

Fig. 7 is a view of a portion of the plug compartment with the operating sleeve moved to the switch closing and plug locking position;

Fig. 8 is a view similar to Fig. 5 of a modified form of my invention in which two switches are housed within a flame-proof compartment and are controlled by common operating mechanism;

Fig. 9 is a sectional view taken on the line 9—9 of Fig. 8, looking in the direction of the arrows, showing particularly the operating mechanism for one of the switches;

Fig. 10 is a sectional view taken on the line 10—10 of Fig. 8, showing the operating mechanism for the other switch; and

Fig. 11 is a wiring diagram showing the con-

2

nections to the mining machine motor and the auxiliary motor.

This application is a division of my co-pending parent application, Serial No. 485,291, filed May 1, 1943, for a Switch and plug box, now Patent No. 2,441,465, dated May 11, 1948.

In gaseous mines such as gaseous coal mines it is necessary in order to meet the requirements of the Bureau of Mines to provide what is known as permissible or explosion or flame-proof equipment and to this end it is necessary to prevent the exposing of any electrical conductors, plugs or the like, in which it is possible to have the exposed conductors or plugs energized even though current may not be flowing in them. In other words, a voltage must not be present on any exposed electrical conductors or plugs.

In the apparatus which I have provided, a disconnectible plug is provided and mechanism which forms a permanent part of the complete plug is provided to control a switch which disconnects the plug from the source of voltage before the plug can be exposed, the plug itself being contained in an explosion, or flame-proof compartment when it is in an electrical conducting condition.

Referring to the drawings it will be seen that I have provided a permissible, explosion or flame-proof box, housing, or enclosure 10 which includes a relatively large switch compartment or enclosure 11 and an integral extension forming a plug compartment, housing or enclosure 12. The bottom, side and end walls of the explosion or flame-proof switch compartment 11 are integrally formed of such material as cast iron and the top is formed by a removable top plate 13, removably attached by a plurality of machine screws 14. The rear wall of said compartment 11 is provided with a pair of stuffing boxes 15 each adapted to receive a single conductor cable and provide a flame-proof connection therewith.

In some arrangements which I have provided, a plurality of boxes 10 are mounted upon a common base and are electrically interconnected and to this end the rear of the compartment 11 is also preferably provided with openings 16 on opposite sides thereof which, when a single box is employed, is either filled by a removable plug or the opening is not actually formed but is cast solidly close together with the side walls of the box 10. The two cables received by the stuffing boxes 15 lead to a source of potential and consequently they are always energized or "hot" and these cables 55 are connected within the compartment 11 to the

receiving terminals of a combination switch and overload circuit breaker 17.

The plug compartment 12 includes an integrally formed neck 18 which extends horizontally and forwardly from the front wall of the compartment 11 and this neck receives a sleeve 19 having a peripheral outer rim 20, the sleeve 19 being connected to the neck 18 by four spaced machine screws 21 (see Fig. 6). The inner end of the sleeve 19 includes an integral wall 22 which wall acts as a partition to divide the plug compartment 12 into two parts and acts to support two separable parts of an electrical receptacle or socket 23 which is made of insulating material and which is connected to the partition 22 by three bolts 24 (see Fig. 2). Said bolts 24 extend through three openings which can be seen at 25, particularly in Fig. 6 of the drawings, said openings 25 being formed in integral wings of the partition 22 that extend into a central opening 26 formed in the partition 22, as illustrated in dotted lines in Figs. 2 and 6 of the drawings. Said central opening 26 provides for the extension therethrough of bayonet type receiving contacts which are provided in the receptacle 23, this type of electrical receptacle being well known in the electrical art.

It may be mentioned that the plug or receptacle 23 includes an inner portion 27 which has three terminals 28 which are connected to three electrical conductors forming part of a short cable 29 which extends through a stuffing box 30 carried by a pair of arms 31, said stuffing box 30 having a flame-proof fitting between the outer cylindrical surface thereof and a cylindrical opening in the front wall of the switch compartment 11, thus providing a permissible or flame-proof passage-way for the conductors of cable 29. In said compartment 11 two of the conductors of cable 29 are connected to the output terminals of the switch 17 and the third conductor thereof is the ground conductor which is grounded to the box 10 within said compartment 11, as is clearly illustrated in Fig. 1 of the drawings, by being connected to a projection formed integrally with said box 10 and within the compartment 11.

The receptacle 23 also includes an outer portion 32 which is outside or to the left of the partition 22, the two portions 27 and 32 of said receptacle 23 being held together and mounted on the partition 22 by the bolts 24, as above described. Said outer receptacle portion 32 carries three bayonet receiving contacts to receive the three bayonet prongs of a removable plug, as hereinafter described more completely, said plug and receptacle structure being of a type well known in the electrical art.

Mounted upon the end of a three conductor electrical cable 33, which electrical cable may be the source of power for any desired piece of apparatus, I provide what I shall designate as a complete plug 34. It may be stated that the electrical apparatus or device to be operated and to which energy is supplied by the cable 33 may be of any type. By way of illustration it may be stated that the apparatus of my invention has been employed in coal mining apparatus in which the cable 33 energized electrical drills for drilling the mine face in a coal mine and electrical water wagons which provide water to spray the mine face while a cutting machine is cutting a kerf. These are only two illustrations of which many might be given of the type of apparatus in which my device may be employed.

Referring particularly to the structure of the

75 complete plug 34, attention is directed particularly to Figs. 1, 5 and 7 of the drawings. Said complete plug 34 includes a plug holder or main body 35 which includes a handle 36 by which the plug may be connected or disconnected and also includes a cylindrical housing portion 37. Within the housing portion 37 is mounted an electrical insulated plug 38 provided with three bayonet type blades adapted to be projected into the aforementioned electrical contacts carried by the receptacle 23. The electrical plug 38 is attached by three spaced screws 39 to integrally formed ears provided within the hollow interior of the plug holder 35. Rotatably mounted on the outer cylindrical surface of the housing portion 37 is a generally cylindrical sleeve 40 which is provided with a plurality of radially extending lugs 41 (see Fig. 6) which are adapted to be gripped by an operator to rotate said sleeve 40 for the purpose of locking the complete plug 34 in place and simultaneously operating the switch 17 to close its circuit, as hereinafter described more completely.

The sleeve 40 is also provided with a stop member 42 adapted to co-operate with a stationary stop member 43 carried by the rim 20 of sleeve 19 to limit rotary motion of said sleeve 40 in a counter-clockwise direction. The sleeve 40 is preferably made as a brass casting and, of course, 30 the interior surface thereof is cylindrical and of appreciable longitudinal length so as to have contact over a large bearing area with the outer cylindrical surface of the housing portion of plug holder 35. Also the outer surface of the sleeve 35 40 is cylindrical and has an appreciable bearing area with the inner cylindrical surface of the sleeve 19.

These two relatively large bearing surfaces between the sleeve 40 and the housing portion 37 40 in one instance and the sleeve 19 in the other instance are for the purpose of insuring a permissible, explosion or flame-proof construction for the plug compartment 12. In other words, should an explosion take place within said compartment 12, due to it becoming filled with explosive gas in a gaseous mine, which gas was ignited by an electric spark, the explosion in the compartment 12 would not be capable of discharging a flame outside said compartment. This 50 is because the hot expanded gases resulting from the explosion would have to travel over such elongated paths along the surfaces on both the outside and inside of the sleeve 40 as to cool said gases sufficiently to prevent the appearance of a flame outside said compartment 12. The sleeve 40 is mounted for rotary movement with respect to the plug holder 35 as previously described but after being once assembled it becomes a permanent part of the complete plug 34 and is held 55 against longitudinal movement with respect to said plug holder 35 by virtue of the fact that the inner end of the cylindrical housing 37 is provided with a peripheral ledge 44 adjacent which the inner end of the cylindrical housing 37 abuts. 60 The outer end of the sleeve 40 is held against longitudinal movement with respect to the plug holder 35 by a wire ring 45 which fits into a groove in said plug holder 35 and the ends of which are perfectly welded together after it is 65 inserted in said groove.

It is an important feature of my invention that after the complete plug 34 is inserted in place to effect an electrical connection and with the parts in position as illustrated in Fig. 1 of the drawings it is possible by rotating the sleeve

40, by grasping the lugs 41, to lock the complete plug 34 in place, thus preventing its removal and simultaneously closing the switch 17 by moving it to the "on" position. To this end the sleeve 40 is provided with a lug or actuator in the form of an integral extension or key 46 which is formed as a segment of a cylinder and which is provided with an arcuate slot or groove 47 (see particularly Fig. 4) which groove upon rotation of the sleeve 40 in a clockwise direction from the position illustrated in Fig. 1 to the position illustrated in Fig. 7 receives a portion of the partition 22 and as a consequence will prevent removal of the complete plug 34 and thus will prevent breaking of the electric circuit by the electrical plug 38 and receptacle 23.

At the same time that the complete plug 34 is thus locked in position it simultaneously is effective to close the switch 17 (which switch 17 otherwise cannot be closed) by moving the switch operating mechanism hereinafter described. To this end there is provided within the switch compartment 11 a longitudinally extending operating rod 48 slidably mounted in a bore 49 formed in a boss 50 at the rear end of the switch compartment 11 and sliding through a bore in a boss 51 (see Fig. 4) in the front wall of said compartment 11.

The rod 48 of the switch operating mechanism is provided with a yoke 52 (see Fig. 3) which has sliding contact with the top plate 13 and which is removably attached to the rod 48 by a screw 53. The yoke 52 acts as one abutment for a coil spring 54 which is coiled about the rear end of the rod 48 with the opposite end abutting the boss 50. As a consequence of this structure the rod 48 is held against rotation and is mounted for longitudinally sliding movement and is resiliently urged or held in one position, that is, to the left as viewed in Figs. 1 and 5 of the drawings.

Intermediate its ends the rod 48 is provided with a transverse groove 55 which receives an operating member 56 of the switch 17, said groove 55 being provided on opposite sides of said member 56 with removable leather blocks 57 to provide cushion means for the operating member 56.

With the members in the positions illustrated in Fig. 1 of the drawings, the switch 17 is in the "off" or open circuit position and to move it to the "on" or closed circuit position the rod 48 is shifted to the right carrying with it the operating member 56.

It may be stated that if the overload relay of the combined switch and relay 17 opens in response to excessive current, this will take place only when the switch 17 is closed and to reset the overload relay the operating member must be moved to the "off" position and then to the "on" position which can be effected, of course, by operating the rod 48.

The left-hand end of the rod 48 extends into the plug compartment 12 and as particularly illustrated in Fig. 4 of the drawings it is to be noted that the extreme left-hand end of said rod 48 is positioned adjacent and behind a portion of the partition 22. As a consequence, it is practically impossible for anybody to manipulate the rod 48 except by inserting the complete plug 34 and rotating the sleeve 40 to effect its operation in a manner now to be described.

It may be pointed out that the lug, extension or key 46 of the sleeve 40 extends through a very narrow arcuate elongated slot 58 (see Fig. 2) which is formed in the partition 22 and when

the parts are assembled as illustrated in Fig. 1 of the drawings this elongated slot 58 is the only effective opening in the partition 22 since all other openings have been closed by the receptacle 23.

It is to be noted that due to the small width of the slot 58 it would be extremely difficult for any person to extend a tool into it and get a working contact with the rod 48 to move it, particularly in view of the fact that the left-hand end of the rod 48 is behind a wall of the partition 22. This difficulty is further increased by the fact that the end of the rod 48 is provided with an anti-friction roller 59 and if a tool such as a screw driver would project through the slot 58 it could not easily be caught on the rod 48 because the roller 59 would tend to cause it to roll off. The roller 59 provides an anti-friction bearing between the operating rod 48 and a cam surface 60 which is formed on the extension or key 46. Thus unauthorized closing of switch 17 is prevented when plug 34 is removed. This precludes energization of the contacts in compartment 12 except when it is in a flame-proof condition.

It is obvious that when the sleeve 40 is rotated in a clockwise direction from the position illustrated in Fig. 1, the cam surface 60 (see Fig. 4) will contact with the roller 59 forcing the rod 48 to the right, as viewed in Figs. 1, 4 and 5, and continued rotation of said sleeve 40 and extension 46 will move the rod 48 sufficiently to the right against the action of the spring 54 to operate the member 56 to move the switch 17 to the circuit closing or "on" position. This "on" position of the rod 48 and roller 59 and the cam surface 60 is illustrated in Fig. 7 of the drawings and the position of the roller 59 is indicated in the "on" position in dotted lines in Fig. 4 of the drawings, both with respect to its position on the rod 48 and with respect to its position relative to extension or key 46. Thus with the sleeve 40 rotated in a clockwise direction with the parts all assembled the switch 17 will be "on" and the complete plug 34 will be locked so as to provide the complete flame-proof character of the plug compartment 12.

It may be noted that the cam surface 60 provides a hump on the extension or key 46 which will frictionally hold the parts in the "on" or circuit closing position as illustrated particularly in Fig. 7 of the drawings.

The operation of the device is believed clear from the above description but to review it briefly it will be assumed that if an operator desires to connect an auxiliary device that is to be operated, such, for example, as the motor of an electrical drill which is provided with the electrical cable 33 and a complete plug 34, the complete plug 34 will be inserted by inserting the sleeve 40 into the sleeve 19. To insure the proper position of the parts, the top of the handle 36 is preferably provided with a label, marked "Top" as illustrated in Fig. 5 of the drawings.

It is, of course, necessary that the bayonet contacts of the plug 38 be received properly by the receptacle 32 and to insure this alignment the plug has a fixed relation to the cylinder housing portion 37 of the plug holder 35 which is determined when the parts are rigidly assembled and this is determined by a small pin 61 (see Fig. 7) which projects into a notch 62, the pin 61 being carried by the cylinder housing portion 37 and the notch 62 being formed in the electrical plug 38. The plug holder 35 can have only one position with respect to the sleeve 19 and this is ef-

fected by virtue of a pin 63 (see Fig. 2) which is carried by the partition 22 and which projects into a slot or groove 64 formed on the inner end of the plug holder 35. These two co-operating parts 63 and 64, of course, prevent rotation of the plug holder 35 when the sleeve 40 is rotated to lock the complete plug 34 and to operate the switch 17.

Assuming, therefore, that the parts have been inserted as above described, the electric contact will be made between the electrical plug 38 and receptacle 23 to complete the electric circuit to the switch 17 from the cable 33. The plug compartment 12 will now be completely closed providing a flame-proof or permissible compartment. The sleeve 40 will then be rotated by an operator grasping the lugs 41, which are in the nature of an operating handle for rotating said sleeve 40 in a clockwise direction. When this rotation is completed the complete plug 34 will be locked in position by virtue of the slot 47 receiving a portion of the partition 22. This, of course, will prevent removal of the complete plug 34 until sleeve 40 is rotated to a reverse position.

The condition of the parts with said complete plug 34 locked is illustrated in Fig. 7 of the drawings. This rotary motion in addition to locking the complete plug 34 will also close the switch 17 by moving the operating rod 48 against the action of the spring 54 or, in other words, move it to its "on" position. This is effected by the cam surface 60 of the extension or key 46 pressing against the anti-friction roller 59 and consequently forcing the operating rod 48 rearwardly, which movement operates the member 56 to close the switch 17. The form of the cam surface 60 with the final "on" position, will tend to hold the parts in the "on" or locked position, the said spring pressed roller 59 operating as a spring detent.

After the drill has been used to the extent desired, in case it is desired to disconnect the cable 33 so as to take the drill to another part of the mine, the handle provided by the lugs 41 will be rotated in a counter-clockwise direction and under the action of the spring 54 the rod 48 will move to the left, or forwardly to open the switch 17, or move it to its "off" position, and the complete plug 34 will be free so that it can be pulled out by longitudinal pull on the handle 36.

It is to be particularly noted that the switch compartment 11 is a flame-proof compartment under all conditions. The plug compartment 12 is made flame-proof whenever the complete plug 34 is inserted and it is impossible to energize any of the electrical connectors in the plug compartment 12 until the complete plug 34 has been locked in position because the locking of said complete plug in position is a necessary incident to the operation of the control switch 17. It is also evident that I have made it extremely difficult, if not impossible, for any one to operate the switch 17 to its "on" or closed position except by inserting the complete plug 34 and adjusting it to its locked position. As a consequence, it is practically impossible to provide a voltage in the plug compartment 12, by any manipulation of switch 17, except when the complete plug 34 is locked in place and said plug compartment or housing 12 is closed and flame-proof in character. In other words, when the plug 34 is removed, the receptacle 23 is dead.

Features of the invention herein described in connection with Figs. 1 through 7 are claimed

in my parent application, Serial No. 485,291, hereinbefore identified.

In Figs. 8, 9 and 10 of the drawings I have shown a modified arrangement in which the structure is the same as that previously described unless a contrary fact is indicated. In this modified structure I have provided a toggle switch 65 which is placed in the flame-proof switch compartment 11 alongside the switch 17. The toggle switch 65 controls a device to be operated such as the motor which drives the cutter chain of a mining machine and this switch 65 and switch 17 are so interlocked that the former is in the "off" position while the latter is in the "on" position and vice versa. This is an important safety feature and precludes operation of an auxiliary motor or device such as a hand-operated electric drill except when the cutting mechanism of the mining machine is shut off. To provide this interlock, an operating arm 66 is carried by the rod 48 and this arm 66 preferably is provided with spaced contact bearing lugs 67 which have sliding frictional contact with the cover plate 13. The arm 66 is shown L-shaped and the outer end thereof is provided with a U-shaped yoke 68 (see Fig. 10) which straddles the operating member 69 of the switch 65. As illustrated in Figs. 8, 9 and 10 of the drawings, the switch 17 is open or is in the "off" position. When the rod 48 is moved to the right, as viewed in Fig. 8, by the operation of the cam surface 60, as previously described in connection with Figs. 1 to 7, inclusive, the rod 48 will be moved to the right and switch 17 will be closed while switch 65 will be open.

The electrical circuit in which two switches 17 and 65 as well as the complete plug 34 and associated cable 33 are an important part, is illustrated in Fig. 11 of the drawings. As here illustrated, the motor 70 is, for example, the motor which drives the cutter chain of a mining machine and purely by way of illustration it may be similar to the motor illustrated in detail in Fig. 37 of the patent to R. K. Jeffrey et al., 2,263,779, dated November 25, 1941. This electric motor is energized from a pair of main line conductors 71 and is controlled by a magnetic contactor or switch 72, that is, the switch or contactor 72 controls the energization of motor 70 from conductors 71. The contactor 72 is under the control of the toggle switch 65 and a starting switch 74 over an obvious circuit so that whenever the toggle switch 65 is closed or in its "on" position the contactor 72 may be energized by closing the switch 74 to drive the motor 70 and when toggle switch 65 is open or in its "off" position, contactor 72 cannot be energized to start the motor 70.

Branch conductors lead from main conductors 60 71 directly to switch 17 which controls the conductors of short cable 29 and of cable 33 through the plug 38 and receptacle 23. Cable 33 leads to an auxiliary motor 73 which may be the motor of any auxiliary apparatus, one illustration of which may be the motor of a hand drill such as illustrated in Patent No. 2,159,087 to R. K. Jeffrey, dated May 23, 1939. This hand drill is understood to be only one illustration of various types of equipment which may be attached to cable 33.

In addition to the features above described in connection with the devices of Figs. 1 to 7, it is evident that the devices of Figs. 8 to 11 provide a safety feature, in that the auxiliary device such as the hand drill, can only be operated when the

circuit to the cutting motor of the mining machine is open. As a consequence, an operator working at the face of a mine room is protected against the extreme hazard which might otherwise be occasioned by the operation of the cutting mechanism of the mining machine.

Obviously those skilled in the art may make various changes in the details and arrangement of parts without departing from the spirit and scope of my invention as defined by the claims hereto appended, and I therefore wish not to be restricted to the precise construction herein disclosed.

Having thus described and shown an embodiment of my invention, what I desire to secure by Letters Patent of the United States is:

1. In electrical apparatus, the combination with a flame-proof box, of a pair of switches in said box, a pair of electrical motors, electrical circuits for said motors including said switches, one for each circuit, common operating mechanism for said switches constructed and arranged to insure opening of one of said switches when the other is closed, one of said circuits including an electrical cable having a plug, a flame-proof plug and receptacle compartment therefor carried by said flame-proof box, said common switch operating mechanism extending from said flame-proof box into said flame-proof plug and receptacle compartment, means resiliently holding said switch operating mechanism in one position, and means on said plug for moving said switch operating mechanism to operate both of said switches as aforesaid.

2. In electrical apparatus, the combination with a flame-proof box, of a pair of switches in said box, a pair of electrical motors, electrical circuits for said motors including said switches, one for each circuit, common operating mechanism for said switches constructed and arranged to insure opening of one of said switches when the other is closed, one of said circuits including an electrical cable having a plug, a flame-proof plug and receptacle compartment therefor, said common switch operating mechanism extending from said flame-proof box into said flame-proof plug and receptacle compartment, means resiliently holding said switch operating mechanism in one position, and means on said plug for moving said switch operating mechanism to operate both of said switches as aforesaid.

3. In electrical apparatus, the combination with a flame-proof box, of a pair of switches in said box, a pair of electrical motors, electrical circuits for said motors including said switches, one for each circuit, common operating mechanism for said switches constructed and arranged to insure opening of one of said switches when the other is closed, one of said circuits including an electrical cable having a plug, and a flame-proof plug and receptacle compartment therefor carried by said box.

4. In electrical apparatus, the combination with a box, of a pair of switches in said box, a pair of electrical motors, electrical circuits for said motors including said switches, one for each circuit, common operating mechanism for said switches constructed and arranged to insure opening of one of said switches when the other is closed, one of said circuits including an electrical cable having a plug, a plug and receptacle compartment therefor, said common switch operating mechanism extending from said box into said plug and receptacle compartment, means resiliently holding said switch operating mech-

anism in one position, and means on said plug for moving said switch operating mechanism to operate both of said switches as aforesaid.

5. In electrical apparatus, the combination with a box, of a pair of switches in said box, a pair of electrical motors, electrical circuits for said motors including said switches, one for each circuit, common operating mechanism for said switches constructed and arranged to insure opening of one of said switches when the other is closed, one of said circuits including an electrical cable having a plug, a plug and receptacle compartment therefor, said common switch operating mechanism extending from said box into said plug and receptacle compartment, and means on said plug for moving said switch operating mechanism to operate both of said switches as aforesaid.

6. In electrical apparatus, the combination with a flame-proof box, of a pair of switches in said box, a pair of electrical motors, electrical circuits for said motors including said switches, one for each circuit, and common operating mechanism for said switches constructed and arranged to insure opening of one of said switches when the other is closed.

7. In electrical apparatus, a combination including a pair of switches, a pair of electrical devices to be operated, electrical circuits for said devices including said switches, one for each circuit, a common operating mechanism for said switches constructed and arranged to insure opening of one of said switches when the other is closed, one of said circuits including an electrical cable having a plug, a plug receptacle therefor, said common switch operating mechanism extending into said plug receptacle, means resiliently holding said switch operating mechanism in one position, and means on said plug for moving said switch operating mechanism to operate both of said switches as aforesaid.

8. In electrical apparatus, a combination including a pair of switches, a pair of electrical devices to be operated, electrical circuits for said devices including said switches, one for each circuit, a common operating mechanism for said switches constructed and arranged to insure opening of one of said switches when the other is closed, one of said circuits including an electrical cable having a plug, a plug receptacle therefor, said common switch operating mechanism extending into said plug receptacle, and means on said plug for moving said switch operating mechanism to operate both of said switches as aforesaid.

9. In electrical apparatus, a combination including a pair of switches, a pair of electrical devices to be operated, electrical circuits for said devices including said switch, one for each circuit, a common operating mechanism for said switches constructed and arranged to insure opening of one of said switches when the other is closed, one of said circuits including an electrical cable having a plug, a plug receptacle therefor, and means on said plug for moving said switch operating mechanism to operate both of said switches as aforesaid.

10. In mining apparatus, the combination with a mining machine motor, of an auxiliary motor, circuits for said motors including an individual switch for each, an electrical cable forming at least part of one of said circuits and having a removable plug, a flame-proof box within which both of said switches are housed, a plug compartment on said box having an electrical recep-

11

tacle therein, co-operating means on said plug and compartment to provide a flame-proof enclosure when said plug is inserted in said receptacle, and means for simultaneously operating both of said switches to move one to open position and the other to closed position whereby only one of said motors can be operated at a time.

11. In mining apparatus, the combination with a mining machine motor, of an auxiliary electrical device to be operated, circuits for said motor and auxiliary device including an individual switch for each, an electrical cable forming at least part of the circuit for said auxiliary device and having a removable plug, a flame-proof box within which both of said switches are housed, a plug compartment on said box having an electrical receptacle therein, co-operating means on said plug and compartment to provide a flame-

12

proof enclosure when said plug is inserted in said receptacle, and means for simultaneously operating both of said switches to move one to open position and the other to closed position whereby said auxiliary device can be operated and said motor cannot be operated and vice versa.

WALTER J. BAUROTH.
